UNITED STATES PATENT OFFICE.

AUSTIN TARPY, OF BRUSSELS, ILLINOIS.

CONVERTIBLE WAGON-BODY.

1,258,500.

Specification of Letters Patent. Patented Mar. 5, 1918.

Application filed September 26, 1917. Serial No. 193,807.

To all whom it may concern:

Be it known that I, AUSTIN TARPY, a citizen of the United States, residing at Brussels, in the county of Calhoun and State 5 of Illinois, have invented certain new and useful Improvements in Convertible Wagon-Bodies, of which the following is a specification, reference being had to the accompanying drawings.

10 This invention relates to wagon bodies, and particularly to convertible wagon bodies.

The general object of my invention is to provide a very simple wagon body so constructed that the body may be used as an ordinary wagon body, may be converted into a hay rack, or into a closed or open box such as is used for the transportation of animals.

20 A further object of the invention is to provide a body of this character including side boards braced in a vertical position against the stakes or standards of the frame, and provide rack boards so connected to the 25 body that they may be turned into a horizontal position or to positions midway between a horizontal and a vertical.

A further object is to provide improved connecting members or braces between the 30 side boards bracing the side boards of the body from each other, these connecting members being formed to engage end gates, and also formed to receive angular rack supporting members which are detachably 35 disposed in the ends of these braces.

Other objects will appear in the course of the following description.

My invention is illustrated in the accompanying drawings, wherein:

40 Figure 1 is a top plan view of my improved wagon body arranged as a hay rack; Fig. 2 is a cross sectional view looking toward the forward end of the wagon body, when arranged as a hay rack, showing in 45 dotted lines the manner in which the rack boards may be lifted to a vertical position to form an open box;

Fig. 3 is a sectional view looking toward the front showing the rack boards raised to 50 a vertical position and showing intermediate boards 31 in place to form a closed body;

Fig. 4 is a perspective view of the brace 18 and the bracket 25; and

55 Fig. 5 is a perspective view of one of the brackets 24.

Referring to these drawings, 10 designates oppositely disposed vertical side boards, and 11 the bottom board of the wagon. These side boards are disposed 60 preferably in a parallel relation and are held in this relation by a plurality of transversely extending irons or braces 12, 13 and 14. The braces 12 are alike and each brace comprises a transverse cross bar having upwardly turned standards 15, these standards at their upper ends being laterally turned as at 16 and being formed with openings 17. The side boards 10 are attached to these standards by means of screws or bolts 19 or 70 in any other suitable manner. The transverse brace or iron 14 has the same form as the braces 12, but the uprights or standards 15 are formed with inwardly projecting flanges 20 to receive an end gate. The 75 brace or iron 13 has substantially the same form as the braces 12 or 14 but it is provided with the inwardly extending flanges 20 for the reception of an end gate, and also with a forwardly deflected upwardly 80 bowed arch 21. Furthermore, the bent extensions 16 are formed with circular apertures 22 instead of with the rectangular apertures which are formed in the extension 16 of the members 13 and 14. It will be 85 understood that the iron 13 is formed at the forward end of the body.

The body, as heretofore described, forms an ordinary wagon box having relatively shallow sides and in order to convert the 90 wagon into a hay rack, I provide the longitudinally extending rack boards 23, and a plurality of supporting brackets 24 and 25 to which these boards 23 are attached. The brackets 24 are angularly formed and are 95 made of relatively flat iron so as to provide a portion which extends out beneath the corresponding board and to which the board 23 is connected by screws and a portion 26 which is adapted to extend downward 100 through the corresponding slot 17 and normally bear against the side face of the corresponding board 10. The bracket 25 is right angular in form, but is circular in cross section, and is held to the boards 23 105 by U-shaped bolts 27, through which the bracket may rotate for a purpose which will be later stated. This bracket at its extremity is angularly bent to form a stop 28 to prevent the bracket from being withdrawn from its engagement with the board 23. It will be seen, of course, that the an-

gular ends of these brackets extend through the circular apertures 22 in the ends of the iron 13. Preferably the extremities of the brackets 24 are provided with perforations 5 29 for the attachment of chains or braces. The brackets 24 are all formed with bolt holes whereby rack boards, such as 23, may be attached to the respective brackets.

When the body is to be used as a hay 10 rack; the brackets 24 and 25 are disposed in horizontal position as are the rack boards 23 and the angular ends 26 of the brackets bear against the side walls or boards 10. When it is desired to convert the hay rack 15 into a relatively deep wagon box, the brackets are turned up to a vertical position and slide downward through the slots 17 and 22 until the boards 23 rest upon the upper edges of the boards 10, as illustrated in 20 Fig. 2, the angular ends 26 of the brackets extending laterally outward. The angular ends of the brackets 25 would, under these circumstances, project outward and would interfere with the turning movement of the 25 front wheels and it is for this reason that I so mount the brackets 25 upon the boards 23 that the brackets may be turned so as to carry the angular ends flat against the sides 30 10 and thus out of the way of the front wheels when the front wheels are cramped, as in Fig. 3.

By providing the perforations 29, chains 35 may be used to hold the rack boards and their corresponding brackets in an upwardly and outwardly inclined position. Of course it will be understood that end boards are to be inserted between the flanges 20 when the boards 23 are turned up to a vertical position. In order to make a still deeper and 40 solid wagon box, I may dispose boards 31 between the rack boards 23, these boards being bolted to the long legs of the brackets 24 and 25. These rack boards 23, in practice, will be about 6" wide. Therefore, if 45 the two outer rack boards 23 and 31 be left off, I increase the height of the side walls by 6". If the outer and inner rack boards are left on I increase the height of the side walls by about 18" with a space be- 50 tween the rack boards and if the third rack board is used, I increase the height of the body about 18", but I have a solid side wall or tight box. If no side boards are wanted and if the rack is not wanted, it is 55 obvious that the supporting irons 24 and 25 may be slipped out from their engagement with the bracing irons 12, 13 and 14, thus leaving the main wagon body for any use wanted.

60 It will be seen that I secure a convertible wagon body, without the necessity of using braces extending from the lower edge of the main wagon box to the outer edge of the extension boards, and this is one of the 65 objects of this invention. It will further

be seen that this construction is very simple, may be cheaply made, and that it provides for a very strong and rigid connection of the boards 10 to the body of the wagon box and for a quickly adjustable and quickly 70 detachable engagement of the rack boards or extension boards with the wagon box.

In Fig. 3, I show the rack boards raised to a vertical position to form a solid sided box, the rack boards being held in this position by means of the chain 33 and by transverse bolts 34 passing in front of the end gate 32.

Having described my invention, what I 80 claim is:—

1. In a wagon, a wagon box having side boards, braces connecting the bottom to the side boards and extending beyond the side boards and formed with apertures at their ends, a plurality of angular brackets insertable through the apertures, the brackets being angular in form to provide each a portion extending horizontal, a portion extending down and bearing flat against the side walls of the wagon, and extension 90 boards mounted upon said brackets, the forward brackets being rotatably connected to the extension boards.

2. In a wagon, a wagon box having side boards, braces connecting the bottom to the side boards and extending beyond the side boards and formed with apertures at their ends, a plurality of angular brackets insertable through the apertures, the brackets being angular in form to provide each a portion extending horizontal, a portion extending down and bearing flat against the side walls of the wagon, and extension boards mounted upon said brackets, the forward brackets being rotatably connected to the extension boards, and said brackets at their extremities being perforated for the engagement of connections to hold the brackets and extension boards from lateral outward movement when disposed in an upwardly 100 and outwardly inclined position.

3. A wagon box comprising a bottom, a plurality of approximately U-shaped bracing irons attached to the bottom and extending upward on each side and then extending laterally outward, side boards attached to the upward extensions of the bracing irons, said irons extending beyond the side boards and being apertured, brackets, each angular in form to provide a leg extending through the aperture of the corresponding iron, and a leg extending horizontally, the brackets being slidably disposed in said apertures, and extension boards attached to said brackets, the outer ends of the brackets being perforated for the engagement of connections to hold the brackets and extension boards from lateral outward movement when disposed in upwardly extending position.

4. In a wagon box, a bottom, side walls, a plurality of transversely extending bracing irons connecting the bottom to the side walls, each iron being approximately U-shaped in form and having its upper ends laterally bent beyond the upper edges of the side boards and apertured, the forward and rear irons being formed with end gate receiving flanges, and the upwardly extending portions of the forwardmost iron being connected by an upwardly bowed arch, angular brackets slidingly disposed within the apertures and the extremities of the
